UNITED STATES PATENT OFFICE

WILLIAM BLASKEWITZ, OF DETROIT, MICHIGAN, ASSIGNOR, BY MESNE ASSIGNMENTS, TO CLAYTON & LAMBERT MANUFACTURING COMPANY, OF DETROIT, MICHIGAN, A CORPORATION OF DELAWARE

PUMP ASSEMBLY

Application filed September 23, 1926. Serial No. 137,223.

This invention relates to a pump assembly and has to do particularly with the provision of a novel air check connection between the pump assembly and the container for receiving the compressed fluid from the pump.

The object of the present invention is the provision of a compact pump assembly adapted to form a part of a liquid fuel supply unit and adapted to supply the necessary pressure within the container of the fuel supply unit whereby to cause positive feeding of the fuel within the container to the desired point. In addition to being conveniently mounted on the container unit, the pump assembly is connected to the container unit in a novel manner whereby the fluid forced into the container by the pump is not only maintained therein by a normal check, but which compressed fluid forced within the container is positively sealed therein. In other words, I have provided a normal check for the pump assembly connection and a positive check for sealing any fluid that might escape past the normal check member.

This positive sealing member preferably forms a part of the pump assembly itself and also bears a certain connecting relation with the connecting means between the pump and container whereby it not only serves as a novel supporting member but it is also very conveniently positioned whereby it may be actuated at will to permit pumping, or to serve as a positive checking means.

In the drawings:

Fig. 1 is a plan view showing my novel pump assembly and air check mounted on and forming a part of a fuel supply unit.

Fig. 2 is a front elevation of the structure shown in Fig. 1 and also showing the compact arrangement of pump assembly and fuel container whereby the entire unit may be moved relative to a suitable opening.

Fig. 3 is an enlarged sectional view taken on line 3-3 of Fig. 1.

Fig. 4 is a fragmentary sectional view taken on line 4-4 of Fig. 3.

Fig. 5 is an enlarged fragmentary detail view of the connection between the pump assembly and container and the air check therefor.

My pump assembly is designed to be used primarily in connection with liquid fuel containers, which containers form a part of, or are adapted to be connected with suitable liquid fuel burners or vaporizers. Such container may be designated 1 and as shown in Fig. 3, is provided with a suitable elbow connection 2. This elbow connection may be of any form and shape desired, but in the illustrated elbow it is of standard right angular shape, and provided with a suitable passageway 3 which extends vertically and horizontally in conformity with the general contour of the elbow.

The central bottom part of this elbow 2, which is designed to extend within the casing of the container 1, is provided with a suitable valve cage 4, adapted to receive a steel ball 5 which serves as a check valve to prevent escape of the fluid under pressure within the container.

The horizontal portion of the elbow 2, or the part extending out of the container, is provided with an inlet which is considerably enlarged relative to the passageway 3. This enlarged portion is connected to the passageway by a suitable tapered portion 6, as best shown in Fig. 5. The extreme inlet end of this horizontal portion of the elbow is drilled and tapped, as at 7, and the portion between the taper 6 and the threads 7 is drilled, as at 8.

The pump casing, or cylinder, may be designated 10, and such casing is provided with a suitable pump bottom, or what may be termed a cylinder head 11. This cylinder head is cup-shaped to fit the end of the casing 10 and is provided with a suitable threaded extension 12 which is adapted to have screw fitting relation with the threaded portion 7 of the elbow 2. The forward end of this projection 12 terminates in the tapered pin 13 which is complementally formed with respect to the tapered seat 6. The cylinder head, or cap 11, is provided with a passageway 14 which extends longitudinally of the threaded portion 12, but which terminates and extends laterally back of the tapered portion 14, as clearly shown in Figs. 3 and 5.

The portion 8 of the elbow 2 is sufficiently

cut away whereby to form an annular chamber around the pin 13, whereby when the pin 13 is backed away from the tapered seat 6 the compressed air may be easily forced in and around the annular channel formed between the separated tapered portions 13 and 6. The lateral orifice of the passageway 14 is therefore always open and the tapered pin 13 may be forced against the tapered seat 6 without in any way clogging or otherwise defacing such lateral port. It will be obvious that when the cap 11 is turned to advance the threaded portion 12 and the pin 13 that such tapered pin 13 will be forced against the tapered seat 6 to positively seal the passageway 3 and prevent the escape of any air which might leak past the check valve 5.

The cylinder head or cap 11 has a tight fit with the casing 10 but is movable relative thereto. A quarter or half turn of this cap 11 is all that is necessary to open or close the positive seal 13, and the arrangement of the threads 12 and 7 is such that such quarter or half turn does not effect any appreciable movement of the cap 11.

The cylinder casing 10 is preferably rigidly mounted upon the container 1 by means of the member 15 which may be suitably welded or otherwise secured to the casing 1. This member 15 originally supports and positions the casing 10 as well as the main part of the pump assembly. The other end of the cylinder casing is provided with a suitable cap 16 which also serves as a washer and guide for the piston structure 18 of any standard design.

Although my pump assembly may be used in connection with various types of fuel containers and in connection with various types of burners and stoves, it is preferably used in connection with cook stoves of the type wherein the fuel container and fuel unit are movable as a unit relative to the stove casing. In Fig. 1, I have illustrated a fragmentary portion of a stove casing, as at 20, and as shown in Fig. 2 such stove casing is provided with a suitable aperture or opening 21 in a wall thereof. The fuel container 1 is shown as being supported upon a suitable track member 22 which is secured to the opposite ends of the fuel container, and such track member 22 is adapted to be slidably supported by means of suitable guides 23 which form a part of, or are secured to the stove casing. A suitable generator tube 24 and valve 25 therefor is shown rigidly mounted on the fuel container tank 1, and it will be obvious that by means of the slidable supporting of the fuel tank 1 that the whole unit, including the tank 1, the pump assembly and the generator unit, may be moved into, or out of, the aperture 21, as desired, and without disconnecting the pump assembly or any parts of the fuel supply unit. A suitable pin 26 is provided on the container casing whereby the pump handle may be

safely positioned when it is desired to move the fuel container in or out of the stove casing. This is merely a precautionary measure as the positive lock provided by the cap 11 prevents the handle from being forced outwardly by any fluid pressure. 70

In operation of my novel pump assembly it is only necessary to turn the cylinder head or cap member 11 a quarter or half turn to back the pin 13 away from the valve seat 6. 75 As the cap 11 is very handy this is a very simple operation. The operator is then free to actuate or reciprocate the piston rod 17 to force the air, or other fluid under pressure, into the container 1. Upon the last inward stroke of the piston rod 17, the operator will then turn the cap 11 back a quarter or half turn to advance the point 13 against the seat 6 whereby to positively seal the connection between the pump assembly and the container. 80 This positively prevents any rebound, or expelling action of the piston rod 17 which would otherwise be the case due to leakage of the air past the check valve. The positioning or securing of the pump casing 90 10 in the container by means of the member 15 assists in the arrangement and operation of the cap 11. This arrangement also permits the use of a relatively small pump assembly, and the positioning of the same upon a fuel 95 container to make a neat, simple, compact unit which is always at the desired place when required, and which is conveniently positioned for operation.

What I claim is:

1. In a pump assembly having a pump casing and a fluid pressure container, the combination of an air check connection serving as a mounting between a pump casing and a fluid pressure container, means within the connection for automatically checking the flow of fluid from the container to the pump casing mounted on the surface thereof, and means integral with a movable part of the pump casing for positively checking the 110 flow of air from the container. 100

2. A fuel supply unit for cook stoves or similar structures comprising, a fuel tank and a pump assembly all mounted as a unit and slidably through an opening in the stove 115 casing, a connection for mounting one end of the pump casing upon the tank, a passageway through the connection, a portion of the pump casing having an interfitting relation with said connection whereby relative movement between the two will positively seal said passageway to prevent movement of the pump rod, and means forming a part of the tank adapted to hold said pump rod in innermost position. 120

3. The combination of a fluid container having permanently mounted thereon a pump casing, said casing having a rotatable closure at one end thereof, a check valve member permanently mounted on said con- 130

5 tainer for connecting same with said pump and closure, said closure having an air valve and said member having an interfitting relation with said closure and a valve seat cooperating with said valve whereby said closure is movable to positively control the passage of fluid between said pump and said container.

10 4. The combination of a pump valve assembly and a fluid pressure container, comprising a pump casing permanently mounted on said container and having an air discharge end cap, said cap having a tapered air valve formed integral therewith, a check valve connection permanently mounted upon said container and in threaded engagement with said cap, said cap being rotatable and said connection having a valve seat cooperating with said valve whereby relative movement between said connection and said cap will cause 15 seating of said valve and valve seat.

20 In testimony whereof I affix my signature.
WILLIAM BLASKEWITZ.
